UNITED STATES PATENT OFFICE.

JULIUS E. LILIENFELD, OF KEW GARDENS, NEW YORK.

HIGH-VACUUM TUBE.

Application filed September 29, 1921. Serial No. 504,088.

To all whom it may concern:

Be it known that I, JULIUS E. LILIENFELD, a citizen of Poland, residing at Kew Gardens, in the county of Queens and State of New York, have invented certain new and useful Improvements in High-Vacuum Tubes, of which the following is a specification.

The present invention relates to high vacuum tubes of the type described in my application Serial No. 364,215 filed March 8, 1920, in which an electronic discharge is started and maintained between "cold" electrodes in close proximity to each other, the vacuum being so high that ionization is substantially excluded.

It has been observed with tubes of this character that in order to prevent the formation of too small focal areas, which would cause the fusion and evaporation of the anodic surfaces before a very heavy milliamperage has been applied, it is desirable to use hollow anodic surfaces.

If the anode has a cavity opposite the cathodically active point, then the cathode beam is distorted by the electric field and no harmful concentration upon single points can take place, i. e. no exceedingly small and relatively overloaded focal spots are likely to be formed.

It is the general object of this invention to make use of this observation to better adapt high-vacuum tubes of the character referred to for various purposes to be more particularly pointed out.

For a full understanding of the invention reference is made to the accompanying drawings in which

Fig. 1 is a fragmentary view partly in section showing one embodiment of the invention;

Fig. 2 is a bottom plan view of the electrode arrangement shown in Fig. 1.

Fig. 3 is a more or less schematic view of another form of device embodying the invention.

Fig. 4 is a bottom plan view of the anode shown in Fig. 3; and

Fig. 5 shows a modification of the form in Figs. 3 and 4.

In Figs. 1 and 2 which represent a high-vacuum tube of the general character above referred to is the anode which is provided with a plurality of cavities 11, 12 and 13. A like plurality of cathodes 14, 15 and 16 are so disposed that their active

points 14^a, 15^a and 16^a are each opposite one of the said cavities. In practice the stems of the cathodes approach the anode laterally and the ends are bent to point substantially axially into the respective cavities.

By varying the distance of the cathodically active points 14^a, 15^a and 16^a from their respective cavities 11, 12 and 13, assuming the geometrical characteristics of the said points to be identical, X-rays of different degrees of hardness can be produced.

Conversely by varying the shape of the cathodically active points, other things being substantially equal, the degree of hardness of the X-rays will vary accordingly.

In the drawings the cathodically active points have different shapes for the purpose just mentioned.

It may be stated that the cavities must be larger in tubes operating under high tension than in tubes for the regular diagnostic work, because cathodic rays of considerable velocity require a larger cavity, to be distorted.

The size of the cavity may also be determined by other considerations. Pin hole camera pictures show that not only the spots of impact of the primary cathode rays but also the whole cavity radiates secondary electrons filling the cavity. Thus for radiographic purposes the size of the cavity must be made to correspond to the size of the focus capable of producing sufficiently sharp pictures.

Figs. 3 and 4 represent an arrangement particularly adapted for radiographic purposes. As above mentioned, it is important for such purposes to limit the origin of the X-ray emanation to a relatively small surface which then acts as a focus to produce shadow pictures of good definition. For most practical purposes a sharp definition is obtained with cavities whose mouth or orifice is approximately 5-6 mm. and whose depth is about 3-4 mm. The cathode may consist of a wire of about 2 mm. diameter having as active point a cone the apex angle of which may be 10°-100°. For producing harder rays suitable for therapeutic work more obtuse angles, (130° or more) may be resorted to.

The cavity 21 in the lower face of the anode 20 may be oval i. e. the axis *m* of the cavity may be directed at an angle to the

anode. The cathode 22 terminates in a more or less sharp point 23 closely approaching the cavity or even slightly extending into it as may be found desirable.

5 By the particular arrangement shown the X-ray emanation may take place in the form of a ray cone defined by the angle n , the projection of the oval form upon a plane at right angle to the axis m being circular and 10 the point of the cathode being substantially outside the useful range of X-rays defined by the angle n so that no shadow can be cast by it.

15 It is a particular advantage of the just described arrangement that X-ray emanations from surfaces other than the cavity are practically avoided. This is due, no doubt, to the fact that the electrons tending to pass out of the cavity are restrained by 20 the intense field between the mouth of the cavity and the cathode point.

Another form for still more effectively eliminating the possibility of a shadow due to the interception of the useful X-rays by 25 the cathode is shown in Fig. 5. In this form the angular disposition of the cavity relatively to the axis of the anticathode may be similar to the arrangement shown in Fig. 3 or may be like in Figs. 1 and 2. The 30 cavity, however, is not disposed within the planes defined by the sides of the anticathode but is intersected by one side. The disposition of the cavity 25 and the cathode point 26 is such that the cone of X-ray emanation is projected clear of the cathode point. Within the zone delimited by the angle γ there is undisturbed radiation.

40 For the purposes of illustration I have indicated only a single cavity in Figs. 3 and 5. It is understood, however, that there may be any desired plurality of groups of 45 cavities and cathodically active points differing from each other in various respects to produce rays of different degrees of hardness, as pointed out in connection with Figs. 1 and 2.

In the foregoing I have referred particularly to several ways in which the character 50 of the X-ray emanations can be influenced by the form of the cathode on the one hand and by the form and disposition of the cavity in the anticathode on the other hand and also by the distance and general relationship of the two.

55 It is understood that various other modifications may be made within the scope of the invention.

The surfaces of the cavities hereinbefore referred to are preferably, although not necessarily, surfaces of revolution.

I claim:

1. In high-vacuum devices of the character described, a device for limiting X-ray emanations to a predetermined area, which

comprises an anode having a cavity whose orifice corresponds to the said area and a cathodic point directed into said cavity and in close proximity thereto. 65

2. In high-vacuum devices of the character described, a device adapted for radiographic purposes and having a predetermined focal area, comprising an anode having a cavity whose orifice corresponds to the said area and a cathodic point directed into the area and in close proximity thereto. 70 75

3. In high-vacuum devices of the character described, a device for producing an unobstructed zone of X-ray emanations, which comprises an anode having a cavity extending obliquely relatively to the axis of 80 the anode and a cathodic point directed into the cavity and in close proximity thereto.

4. In a high-vacuum X-ray apparatus, an anode having a cavity whose surface is a surface of revolution and whose projected area corresponds to a predetermined focal area, and a cathode point directed into said cavity and in close proximity thereto. 85

5. In a high-vacuum X-ray apparatus, an anode having a cavity whose surface is a surface of revolution about an axis inclined to the axis of the anode and whose projected area corresponds to a predetermined focal area, and a cathode point directed into said cavity and in close proximity thereto. 90 95

6. In a high-vacuum X-ray apparatus, an anode having in one edge a cavity whose surface is a surface of revolution about an axis inclined to the axis of the anode and whose projected area corresponds to a predetermined focal area, and a cathode point directed into said cavity and in close proximity thereto. 100

7. In high-vacuum devices of the character described, a device comprising an anode having a cavity and a cathode whose active end is directed toward the cavity, the remaining part being bent out of the range of the useful X-ray emanations. 105

8. In high-vacuum devices of the character described, a device comprising an anode having a cavity extending obliquely relatively to the axis of the anode and a cathode whose active end is directed toward the cavity, the remaining part being bent out of the range of the useful X-ray emanations. 110 115

9. In high-vacuum devices of the character described, a device comprising an anode having a cavity in one edge and a cathode whose active end is directed toward the cavity, the remaining part being bent out of the range of the useful X-ray emanations. 120

In testimony whereof, I affix my signature. 125

JULIUS E. LILLENFELD,
